UNITED STATES PATENT OFFICE

124,313

DESIGN FOR A COMBINATION BLADE FOR A
KITCHEN KNIFE OR THE LIKE

William H. Hurlin, Antrim, N. H., and William H. Rosenthal, New York, N. Y., assignors to Goodell Company, Antrim, N. H., a corporation of New Hampshire

Application September 18, 1940, Serial No. 95,176

Term of patent 14 years

To all whom it may concern:

Be it known that William H. Hurlin, of Antrim, county of Hillsborough, State of New Hampshire, and William H. Rosenthal, of 785 West End Avenue, city, county, and State of New York, have invented a new, original, and ornamental Design for a Combination Blade for a Kitchen Knife or the like, of which the following is a specification, reference being had to the accompanying drawing, forming part thereof.

In the drawing:

Fig. 1 is a side view, in elevation of a combination blade for a kitchen knife or the like; Fig.

2 is a front view of the serrated edge, looking in the direction of arrow 2, Fig. 1; Fig. 3 is a longitudinal sectional view taken on the line 3—3, Fig. 1; Fig. 4 is a view of the cutting edge looking in the direction of the arrow 4, Fig. 1; and Fig. 5 is a cross sectional view of the blade, taken on the line 5—5, looking in the direction of the arrow.

We claim:

The ornamental design for a combination blade for a kitchen knife or the like, as shown.

WILLIAM H. ROSENTHAL.

WILLIAM H. HURLIN.
